ROLLER SKATE

Daniel S. Williams, 394 Spruce St., Pottstown, Pa.

Filed Apr. 7, 1960, Ser. No. 60,083

Term of patent 14 years

(Cl. D34—14)

Fig. 1.

Fig. 2.

Figure 1 is a perspective view of the roller skate.

Figure 2 is an elevational view of the front piece of the roller skate, showing the front piece in extended position and removed from the roller skate.

The opposite side of the skate is of substantially the same configuration as the side shown in Figure 1 and the rear portion is of conventional configuration.

I claim:

The ornamental design for a roller skate, as shown and described.
